Inventor

George A. Lane

By Watson E. Coleman
Attorney

UNITED STATES PATENT OFFICE.

GEORGE A. LANE, OF LORAIN, OHIO, ASSIGNOR OF ONE-HALF TO ISAAC A. CHAPPELL
AND ONE-HALF TO JOHN C. HAYES, BOTH OF LORAIN, OHIO.

INNER TUBE.

Application filed October 5, 1922. Serial No. 592,505.

To all whom it may concern:

Be it known that I, GEORGE A. LANE, a citizen of the United States, residing at Lorain, in the county of Lorain and State of Ohio, have invented certain new and useful Improvements in Inner Tubes, of which the following is a specification, reference being had to the accompanying drawings.

This invention relates to certain improvements in inner tubes for pneumatic tires and it is an object of the invention to provide a novel and improved inner tube which is non-elastic and non-expansile and which effectively serves to reduce to a minimum the chances of a blow out.

The invention consists in the details of construction and in the combination and arrangement of the several parts of my improved inner tube whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to describe the same with reference to the accompanying drawings, wherein:—

Figure 1 is a fragmentary view in perspective of an inner tube constructed in accordance with an embodiment of my invention, a portion of the textile lamination being turned back for clarity disclosure;

Figure 2 is a transverse sectional view taken through a device constructed in accordance with an embodiment of my invention; and

Figure 3 is a view in top plan of the textile fabric employed in my inner tube, the intermediate portion thereof being cut away.

As disclosed in the accompanying drawings, my improved tube comprises an inner lamination 1 of rubber, the same being initially molded in tubular form upon a straight metal pole. A textile lamination 2 is then spirally disposed over the inner lamination 1, said fabric being cut on the bias with its opposite end portions obliquely disposed as is clearly illustrated in Figure 3. This lamination 2 is of such length and width whereby the transverse flexing of the

strip 2 will result in the same entirely surrounding the inner rubber lamination 1 with the oblique end portions in overlapping relation as indicated at 3 in Figure 1 and the longitudinal marginal portions of said lamination 2 in slight overlying relation as indicated at 4 in Figure 2.

After the lamination 2 has been applied a lamination 5, comprising a relatively thin sheet of rubber, is wrapped around the lamination 2 in substantially the same manner as has hereinbefore been set forth with respect to the lamination 2. After the tube has been properly builded, the opposite ends of the structure are spliced in the well known manner and the ends of the structure subjected in the well known manner to a vulcanizing operation. The outer lamination 5 is employed to prevent the outer surface of the tube from chafing, while having the lamination 2 cut on the bias, it has been established in actual practice that the tube is materially strengthened as the full benefit is obtained of the strength of both sets of strands comprised in the fabric 2.

An inner tube constructed in accordance with an embodiment of my invention is non-elastic and non-expansile and this is found to be of particular benefit or advantage to reduce the liability of a blow out and also when the carcass or casing has a rim cut, as under such conditions the tube proper will not expand through the casing.

From the foregoing description it is thought to be obvious that an inner tube constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

What is claimed is:—

As a new article of manufacture, an inner tube comprising an inner lamination of rubber the same being initially molded in tubular form, a textile lamination cut on the bias and spirally disposed around the inner

lamination, said textile lamination being of a length and width to surround the rubber lamination, the ends of the textile lamination being obliquely cut and in overlapping relation, the longitudinal marginal portions of said fabric lamination being in slight overlapping relation, and an outer lamination,

10
of sheet rubber wrapped around the textile lamination, the opposite ends of the structure being spliced.

In testimony whereof I hereunto affix my signature.

GEORGE A. LANE.
